UNITED STATES PATENT OFFICE.

LEWIS T. WILCOX, OF PEEKSKILL, NEW YORK.

MANUFACTURE OF WICK-HOLDERS.

1,362,457.

Specification of Letters Patent. Patented Dec. 14, 1920.

Application filed February 10, 1920. Serial No. 357,614.

To all whom it may concern:

Be it known that I, LEWIS T. WILCOX, a citizen of the United States, residing in the village of Peekskill, in the county of Westchester, State of New York, have invented an Improvement in the Manufacture of Wick-Holders and the like, of which the following is a specification.

The improvements relate to the manufacture of annular trough-like structures, such as are commonly used for holding the wick of a wick oil burner used in liquid fuel heating or other stoves.

One of the primary objects of the invention is to reduce the cost of manufacturing such devices by economizing labor and materials and avoiding the loss due to the making of defective articles or "seconds". Another object is to form the article so that it will possess great strength and accuracy of form. Other objects of the invention will appear to those skilled in the art.

The method or process employed and the construction resulting from such method are illustrated in the accompanying drawings referred to in the following description, and forming a part hereof, and in which Figure 1 is a plan of one of the sheets of metal from which the article is formed, by the use of the process, the initial step of producing an offset flange on one vertical edge having been performed. Fig. 2 is an edge view of the same. Fig. 3 is a plan of the sheet of Figs. 1 and 2 formed into a cylinder and showing the second step. Fig. 4 is a similar view after the third step in which the seam is welded and the vertical edges united. Figs. 5 and 5^a are vertical medial sections of the inner and outer shells after the fourth step, in which a bead is made near one edge of the cylinder of Fig. 4, Fig. 5 showing the inner cylinder and Fig. 5^a the outer. Figs. 6 and 6^a are similar views of the same parts as Figs. 5 and 5^a after the fifth step. Figs. 7 and 7^a are similar views of the same parts respectively, after the sixth step. Fig. 8 is a similar view of the parts of Figs. 7 and 7^a after the seventh step, in which the two tubes or cylinders are placed together and united. Fig. 9 shows the dies or formers used in the fifth step and one of the cylinders in position therein, in vertical medial section.

Fig. 10 shows the same parts after this step or operation, with one edge broken away and the parts thus exposed shown on the

plane of the section of Fig. 9. Fig. 11 shows the dies, holder, and one of the tubes employed in the sixth step, on a section similar to that of Fig. 9. Fig. 12 shows the two cylinders and the holder in position for the seventh step or operation in vertical medial section.

As illustrated in the drawings a sheet of metal 1 is taken and provided with an offset 2 on one vertical edge for the purpose of forming a seam. This blank is then placed on a form and bent into a cylinder or tube with the offset portion overlapping the opposite edge and the overlapping edges then welded or otherwise united and reduced to practically a single thickness. In this operation the metal may be stretched or drawn to a sufficient extent so as to make it a true cylinder. These operations are performed with the blanks for both inner and outer tubes.

The inner tube is then placed in a beading machine and provided with an annular inwardly extending bead 3, while the outer tube is similarly treated and provided with an annular outwardly extending bead 4. This operation may be performed by any suitable means.

The outer shell is then placed in the dies 5 or formers 5 and 6 and the bead flattened thereby (see Figs. 9 and 10) to form an annular outwardly projecting flange 7. The inner shell is also placed in dies and acted upon in a similar manner to form the inwardly projecting flange 8, the two flanges 7 and 8 being thus formed of a double thickness of metal. The dies employed in this operation are provided with an annular recess to receive the upper edge of the tube 9 and a downward extension extending below the bead, so that the metal adjacent to the bead is held and prevented from being distorted in this operation. In the dies for the outer shell the recess is indicated at 9 and 10 the downward extension at 10, and the dies for forming the inwardly extending flange from the bead extend below the bead on the outside of the cylinder and have a member filling the bore of the cylinder to the height 105 of the lower edge of the bead while the part corresponding to the part 10 extends only to the upper edge of the bead until the two parts of the dies are brought together.

The outer cylinder is now placed in dies 11, 12, and 13 in inverted position and its lower edge turned over (see Fig. 11), and

the inner tube is similarly treated. The two cylinders are then placed in the holder 14, with their oppositely curled lower edges registering, and the said curled-over portions subjected to the action of a soldering device in which the solder is caused to flow in between them and securely unite them, while their upper edges are held in perfect alinement by the holder.

10 In this manner the trough composed of two concentric tubes with inner and outer alined annular flanges is completed.

I claim as my invention:—

1. The method or process of making wick holders for oil stoves, which consists in taking two pieces of sheet metal, bending them into cylindrical form, one with a greater diameter than the other, forming a circumferential outwardly projecting bead in the cylinder of greater diameter and a similar inwardly projecting bead in the cylinder of lesser diameter, the said beads being near one end and equidistant therefrom, pressing the metal forming said beads so as to fold it together to form annular flanges, and then pressing the said tubes in position one within the other and sealing their ends opposite the flanges.

2. The method or process of making wick holders for oil stoves, which consists in taking two pieces of sheet metal, bending them into cylindrical form, one with a greater diameter than the other, welding and reducing by pressure to substantially a single thickness, the vertical meeting edges of the sheets forming said cylinders, forming a circumferential outwardly projecting bead in the cylinder of greater diameter and a similar inwardly projecting bead in the cylinder of lesser diameter, the said beads being near one end and equidistant therefrom,

pressing the metal forming said beads so as to fold it together to form annular flanges, and then placing the said tubes in position one within the other and sealing their ends 45 opposite the flanges.

3. The method or process of making wick holders for oil stoves, which consists in taking two pieces of sheet metal, bending them into cylindrical form, one with a greater 50 diameter than the other, forming a circumferential outwardly projecting bead in the cylinder of greater diameter and a similar inwardly projecting bead in the cylinder of lesser diameter, the said beads being near one end and equidistant therefrom, pressing the metal forming said beads so as to fold it together to form annular flanges, and then pressing the said tubes in position one within the other and sealing their ends 55 opposite the flanges by turning the said edges toward each other on concentric curves and soldering them together.

4. The method or process of forming wick holders and the like, which consists in forming two concentric cylinders of sheet metal, making an annular projection on the outer surface of the larger tube and the inner surface of the smaller one at coincident 60 points in their length, placing the said tubes 65 in dies and pressing down the edges at one side of the projection and simultaneously compressing the projections to form flanges, forming their other edges into opposite curves, then placing them together in a gage 70 and holder with the flanges resting upon surfaces in the same plane and uniting the said curved edges.

Signed by me this 31st day of January, 1920.

LEWIS T. WILCOX.
